UNITED STATES PATENT OFFICE.

CHARLES LEGRAND AND ALEXANDRE ARMEL, OF PARIS, FRANCE.

ELECTRIC LOCK.

1,052,488.

Specification of Letters Patent. Patented Feb. 11, 1913.

Application filed July 26, 1911. Serial No. 640,570.

To all whom it may concern:

Be it known that we, CHARLES LEGRAND and ALEXANDRE ARMEL, both citizens of the Republic of France, residing in Paris, France, have invented certain new and useful Improvements Relating to Electric Locks, of which the following is a specification.

This invention relates to electrically operated locks, particularly suitable for locking the doors of railway carriages, trams, and the like, said apparatus being controlled from a distance by the sending of an electric current, and serving to keep the door closed so long as an electric current is passing through the electromagnet comprised by the apparatus.

The characteristic of the lock forming the subject of this invention is that it comprises a special arrangement which only allows the lock of a door to be locked when this door is closed. It often happens that a railway carriage door is still open when the train starts. Now it is necessary to provide that such a door can still be closed. This is permitted by the improved arrangement which forms the subject of the present invention, even if the employee charged with the operation of the switch or controlling device for sending the current, has already sent the current into the system to which the lock is connected, because this lock is not affected by the electric current until the door has been closed.

The improved lock of the present invention is illustrated in the accompanying drawings.

Figure 1 is an elevation of the interior of the lock, showing the position occupied when the current is not passing in the electromagnet, the door being open, so that the bolt of the lock and that of the auxiliary switch hereinafter described are not in action. Fig. 2 is a side elevation showing the auxiliary switch in this position. Fig. 3 is an under plan of the lock, showing the relative positions of the main bolt and of the auxiliary bolt. Fig. 4 is a view similar to Fig. 1, showing the position when the current is passing in the electromagnet, the door being closed and the main bolt locked by the bell crank stop lever. Fig. 5 is a side elevation showing the auxiliary bolt in this position. Fig. 6 shows a modification of a detail of Fig. 2.

The lock comprises a case 1 containing a

bolt 2, the rod 3 of which is fitted with a spring 4 bearing against a part 5. One arm of a bell crank lever 6 is adapted in one position to come against the end of the rod 3 of the bolt 2, the bell crank lever being pivoted at 7 and having its other arm pivotally connected to a rod 8 fixed to the soft iron core of an electromagnet 9. A stop 10 limits the rise of the bell crank lever 6 when the current is sent into the electromagnet 9 of the lock. In this position the end of the short arm of the bell crank lever 6 comes above the top of the rod 3 of the bolt, and serves as a stop to prevent this bolt from rising. When the current ceases to be sent into the electromagnet 9, the core of the magnet drops by its own weight, the bell crank lever 6 moves away from 3 and the bolt 2 can be lifted.

It will be understood that with the arrangement just described, the bolt 2 would be locked, and could not allow the door to be closed if the door was not closed before the current entered the electromagnet 9. This drawback is avoided by providing that the current shall pass to the electromagnet 9 not directly but through the medium of an auxiliary switch which closes the circuit automatically only when the door is closed, while the current is cut off if the door is not completely closed. This device comprises a square bolt 11 having only one bevel and fixed to a round rod or stem 12, the upper end of which is tapered or rounded as at 13; this square bolt is fixed on the stem 12 by means of the screw 14 and can be turned in any direction of closing, according to circumstances, whether the door is hinged or sliding. The upper end of the rod 12 works in an angle piece 15 and a coiled spring 16, fitted between this angle piece and the top of the bolt, tends to depress the bolt when this is not lifted by external means, for example, by a keeper 17, which is the case when the door is properly closed.

Opposite the rounded end 13 is a spring contact 18, secured by one of the screws forming one of the supply terminals for the current. Or (see Fig. 6) the rod 13 penetrates between two blades 18¹ of which the ends are bent out. The other supply terminal for the current is connected by the conductor 19 to the beginning of the winding of the electromagnet 9, the wire by which the current leaves the magnet being connected to the mass of the lock; the two

terminals are mounted on an insulating block 20.

It will be understood that on the closing of a door, the lock being mounted for example in the upper part of the door frame, and the latter being provided with a keeper to receive the bolt 2, the bolt 11 will be raised by the keeper 17 which has no hole or socket opposite the bolt 11. The upper end of the rod 12 therefore comes into contact with the spring tongue 18, so that the circuit is closed through the electromagnet 9. When the employee charged with the operation of the controlling switch or switches 15 sends the current into the conductors 21, 22, the circuit is closed between 18, 13, the mass of the lock and the electromagnet 9; the soft iron core is then attracted, and the bell crank lever 6 pivots into position to act as 20 a stop to the bolt 2. If, however, the door has remained open, the bolt 11 will not have been raised, but is kept depressed by its coiled spring 16, so that the upper end 13 of the rod 12 is away from the contact 18, 25 the current through the electromagnet is interrupted, and the locking bolt 2 remains free.

It will be seen from the plan, Fig. 3, that the axis or end of the bolt 2 and that of the bolt 11 are not in alinement, the axial displacement of these two bolts being such that the bolt 2 comes against the keeper 17 and rises before the bolt 11 has commenced to rise. The result is that the upper end of 30 the stem of the raised bolt 2 forms an obstacle which would prevent turning of the bell crank lever 6 under the action of a current which might be sent into the electromagnet 9; this would happen if the bolt 11 had already been raised by the keeper, 35 since this would have made the contact between 13 and 18, thus closing the circuit. It is for this reason that the bolt 11 should not be raised until after the bolt 2, which 40 can then operate completely and go properly home into the keeper. For this reason therefore the two bolts 2 and 11 are axially displaced as described.

The current for operating the lock may 45 be supplied by any source of electricity, for example by primary batteries or accumulators arranged in the luggage vans or guards' brakes at the head or tail of the train. The rotation of the axles of the vans 50 or brakes might also be utilized for driving a dynamo which would supply throughout the travel of the train the electricity necessary for the action of the electromagnets of the locks. This method of producing electricity 55 would have the advantage that when the train stops at stations or on the track, the doors would be automatically unlocked without requirement for any operation on the part of one of the staff of the train.

If the current for the electromagnets

were supplied only by a dynamo driven by the train itself, there would on starting the train, be no current for acting through the electromagnets on the bell crank stop levers for the bolts of the locks, and consequently 70 the doors could be in the unlocked condition. It is easy to remedy this by having in one or more vans or vehicles a permanent source of electricity, primary batteries or accumulators arranged to be put into action on the starting of the train, by the person in charge operating the switch at his disposal; then when the dynamo driven by the axles is supplying a current of sufficient strength, the current from the dynamo will be arranged to cut out the switch or switch off the battery or accumulator circuit and will flow through the electromagnets of the locks. The battery or accumulator current will therefore only serve 80 on the starting of the train.

Claims:

1. A lock for doors, comprising a spring-pressed bolt adapted to automatically yield and spring back into locking position upon 90 closing of the door, electromagnetically operated means for locking said bolt in locking position, and a door actuated contact-device in circuit with said electromagnetically operated bolt-locking means for controlling the operation of said means, said contact-device being located relatively rearward of said bolt in the direction of the closing movement of the door, whereby said electromagnetically operated bolt-locking 95 means remains inoperative until after the locking movement of said spring-pressed bolt.

2. A lock for doors, comprising a spring-pressed bolt adapted to automatically yield 105 and spring back into locking position upon closing of the door, electromagnetically operated means for locking said bolt in locking position, and a spring-pressed contact-device in circuit with said electromagnetically operated bolt-locking means for controlling the operation of said bolt-locking means, said contact-device being adapted to be closed by the closing of the door, whereby said electromagnetically operated means 110 remains inoperative until the closing of the door.

3. A lock for doors, comprising a spring-pressed bolt adapted to automatically yield and spring back into locking position upon 120 closing of the door, a detent for locking said bolt in locking position, an electromagnet controlling said detent, and a spring-pressed contact device in circuit with said electromagnet for controlling the operation 125 of said electromagnet, said contact device being adapted to be closed by the closing of the door, whereby said electromagnet, and the detent controlled thereby remain inoperative until the closing of the door.

4. A lock for doors, comprising a spring-pressed beveled bolt adapted to automatically yield and spring back into locking position upon closing of the door, electromagnetically operated means for locking said bolt in locking position, and a door actuated spring-pressed beveled contact device in circuit with said electromagnetically operated bolt-locking means for controlling the operation of said means, the apex of the bevel of said contact device being located relatively rearward of the apex of the bevel of said bolt in the direction of the closing movement of the door, whereby said electromagnetically operated bolt-locking means 15 remains inoperative until after the locking movement of said spring-pressed bolt.
- 5 In witness whereof, we have hereunto signed our names in the presence of two subscribing witnesses.
- 10 CHARLES LEGRAND.
ALEXANDRE ARMEL.
